GARMENT FOLDER

David A. Freeman, Chicago, Ill.

Application August 5, 1958, Serial No. 52,053

Term of patent 14 years

(Cl. D55—1)

Fig. 1 is a rear perspective view of a garment folder embodying my new design;

Fig. 2 is a front perspective view thereof;

Fig. 3 is a top plan view; and

Fig. 4 is a side elevational view.

The broken lines are for illustrative purposes only.

I claim:

The ornamental design for a garment folder, substantially as shown and described.
